UNITED STATES PATENT OFFICE

1,927,113

LOOSE LEAF BINDER

James C. Dawson, Webster Groves, Mo., assignor
to Elma N. Dawson, Webster Groves, Mo.

Application April 29, 1931. Serial No. 533,714

3 Claims. (Cl. 129—24)

This invention relates to loose leaf binders and has for its objects to provide means for easy and instant assembly of booster lever to the binder mechanism, and to retain the levers in position 5 after assembly.

These and other objects and advantages will become apparent from the specification and the appended drawing in which

Fig. 1 is a vertical, longitudinal section through 10 a portion of the loose leaf binder equipped with a preferred form of booster;

Fig. 2 is a vertical, longitudinal section through 15 a loose leaf binder equipped with an alternative form of booster lever;

Fig. 3 is a bottom plan view of the binder shown 20 in Fig. 1;

Fig. 4 is a bottom plan view of the binder shown 25 in Fig. 2;

Fig. 5 is a vertical, transverse section on the 30 line 5—5 of Fig. 1;

Fig. 6 is a perspective view showing in detail 35 the preferred form of booster lever and toggle plate latch;

Fig. 7 is a perspective view showing in detail 40 the alternative form of lever and retainer; and

Fig. 8 is a further modification of the form of 45 lever illustrated in Fig. 7.

The loose leaf binder illustrated in Fig. 1 is of 50 the well known spring back toggle plate type which comprises a book cover 10 to which is affixed a back plate 11 having a plurality of struck-up loops 12. The spring back of the binder, illustrated at 13, is provided with an aperture 14 giving clearance to the loop 12. The binder mech- 55

anism is held assembled to the back by means of a key 15 which passes under the loop and over the spring back. The toggle plates 16 and 17, bearing the pairs of paper-holding prongs 18, are held in engagement by the articulating buttons 60

19 and are gripped on their outer edges by the spring back 13. For the sake of appearance, a 65 cover 21 is usually sprung over the assembly.

So far, the binder is well known and has been 70 recited merely to identify its individual parts.

The preferred order of assembly is to set the 75 plates within the spring back, apply the cover, and then to attach the booster levers, but with many forms of booster levers, this procedure can- 80

not be followed.

I have made it possible to assemble booster 85 levers to the binder whenever desired by the following means:

The toggle plates 16 and 17 bear a latch-like 90 extension 22, 22 formed upon their ends. The latch comprises a narrow necked portion 23, a

head 24, and a bevelled nose 25 cut at a sharp angle to the longitudinal axis of the toggle plates. The booster lever 26 has a thumb arm 27, a body portion 28, and a toggle-operating arm 29. As indicated in Fig. 6, the body portion 28 bears 60 two slots 40, 40 which are designed to engage the latches 22, respectively.

In assembly, the booster levers are placed in a position in advance of that shown in Figs. 3 65 and 5 with the bevelled nose 25 engaging the inner wall of the slots 40 and the operating lever 29 under the toggle plates, as indicated in Fig. 5. A sharp tap on the booster lever forces the toggle plates 16 and 17 apart against the tension of 70 the spring 13 and finally, as the booster lever is forced inwardly, the nose of the latch clears the slots 40 and the plates then come together with their latches extending past the outer face 30 of the body portion 28 of the booster lever. The booster lever then cannot be disassembled from 75 the apparatus without prying the plates apart, and, as indicated by the figures, the lever is ful- crumed upon the neck 23 and the upper margin of the slot 40.

In the modification illustrated in Figs. 2, 4 80 and 7, the toggle plates 31, 31, have their end portions cut to provide slots 32, 32, bevels 54, 54 and fingers 42, 42. The booster lever 33 comprises a thumb arm 34, a body portion 35, an inwardly extending toggle-operating arm 36, and an upwardly extending retainer 37 which terminates in a sector-shaped head 38.

The assembly of this device may be as follows: The toggle plates 31, 31 are mounted with their 90 outer margins engaged by the spring back 39. The booster lever 33 is then placed with the slots or notches 41, 41 in line with the small fingers 42, 42 and with the retainer 37 bearing against the bevels 54, 54 at the ends of the toggle plates. 95

A sharp tap on the booster will force it to the 100 assembled position shown in Figs. 2 and 4.

A pair of duck-bill pliers or a special assembly tool may be used to separate the adjacent edges of the plates 31, 31, if desired; in which case, less 105 force will emplace the boosters.

The body portion 35 of the Fig. 2 modification is eliminated in the type of booster illustrated in Fig. 8. This lever comprises a slightly curved thumb arm 44 having an extension 45 which protrudes beneath the cover plate 21. The end of this extension is turned downwardly at 46 leaving a small vertical arm 47 which terminates, as in the prior form of lever in the sector-shaped head 48. The toggle plates 49, 49 may be the 110 same as those illustrated in Figs. 2, 4 and 7.

The assembly of this device is secured in the same manner as described for the other forms. The portions of the under surface of the booster lever 44, which are in contact with the extensions 51, 51 on the toggle plates are the pivot points of this arrangement.

It is thus evident that the boosters may be inserted in the binders at any time and once assembled are permanently held in place.

10. What I claim, therefore, is:

1. A loose leaf binder having a pair of dead center articulated toggle plates bearing paper holding prongs, a spring engaging the plates and normally urging the prongs into engagement, a latch upon the terminus of each toggle plate, a booster lever having a thumb arm, a vertical arm and a toggle plate operating arm, and a wedge face upon the latches adapted to engage the sides of the vertical arm and to force the toggle plates outwardly against pressure of the spring in the initial assembly of the apparatus.

2. A loose leaf binder having a pair of articulated toggle plates maintained in engagement by spring means, a transverse slot in each plate adjacent one end, said end of each plate being cut at an angle to the longitudinal axis thereof to form a wedge, and a booster lever which, in co-operation with the wedge, is adapted to force the plates apart upon initial assembly and to be engaged by the walls of the slots to maintain the booster in assembled position.

3. A loose leaf binder comprising a pair of slotted dead-center articulated toggle plates bearing paper holding prongs and having wedge faces adjacent to their ends, a spring engaging the outer edges of the plates and normally urging the adjacent edges together, a booster lever fulcrumed upon the toggle plates and adapted to cooperate with the wedge faces to force the plates apart against the resistance of the spring in the initial assembly.
